UNITED STATES PATENT OFFICE.

GEORGE T. SHEARER, OF ATLANTA, GEORGIA, ASSIGNOR OF ONE-HALF TO EUGENE BART, OF ATLANTA, GEORGIA.

DESIGN FOR A HOUSE-NUMBER BOX.

Application filed March 7, 1924. Serial No. 8,864. Term of patent 3½ years.

To all whom it may concern:

Be it known that I, GEORGE T. SHEARER, a citizen of the United States, residing at Atlanta, in the county of Fulton and State of Georgia, have invented a new, original, and ornamental Design for a House-Number Box, of which the following is a specification, reference being had to the accompanying drawing, forming part thereof.

Referring to the drawing, Figure 1 is a perspective view of a house number box and Figure 2 is an end view of a house number box showing my new design.

I claim:

The ornamental design for a house number box as shown.

GEORGE T. SHEARER.
